Des. 192,097
Patented Jan. 16, 1962

192,097

LACE FABRIC OR SIMILAR ARTICLE

Anton J. Wider, 14 Dianne Court, Clifton, N.J.

Filed Dec. 16, 1960, Ser. No. 63,327

Term of patent 3½ years

(Cl. D47—6)

The FIGURE of the drawing is a plan view of a lace fabric embodying my new design.

I claim:

The ornamental design for a lace fabric or similar article, as shown.
